[57] CLAIM

The ornamental design for computer unit bezel, as shown and described.

DESCRIPTION

FIG. 1 is a top, front, left-side perspective view of a computer unit bezel showing my new design, on an enlarged scale;

FIG. 2 is a front elevational view thereof;

FIG. 3 is a top plan view thereof;

FIG. 4 is a right-side elevational view thereof; the left-side elevational view being a mirror image thereof;

FIG. 5 is a bottom view thereof; and,

FIG. 6 is a top, front, right-side perspective view of a second embodiment thereof, on an enlarged scale, the top and bottom views are similar to the FIG. 4 view, the side view is similar to FIG. 5, and the opposite side view is similar to FIG. 3.

The broken line showing the portions of the disk drives and rear cabinet in FIGS. 1-6 is for illustrative purposes only and forms no part of the claimed design.
